UNITED STATES PATENT OFFICE.

THEODORE F. PHILIPPI, OF EAST ST. LOUIS, ILLINOIS.

CRUSHER.

1,333,727.

Specification of Letters Patent. Patented Mar. 16, 1920.

Application filed November 23, 1917. Serial No. 203,524.

To all whom it may concern:

Be it known that I, THEODORE F. PHILIPPI, a citizen of the United States of America, a resident of East St. Louis, in the 5 county of St. Clair, State of Illinois, have invented certain new and useful Improvements in Crushers, of which the following is a full, clear, and exact description, reference being had to the accompanying drawing, forming a part of this specification.

My invention relates to improvements in crushers, the object being to provide a strong and durable means for crushing, or hammering, and breaking coal and other materials. The new structure preferably includes a crushing ring made of hard material which will not rapidly wear away in service, and this hard material is preferably reinforced by a ring made of strong material which does not engage the material to be crushed. More specifically stated, the periphery of the crushing ring is provided with an annular row of projecting crushing elements adapted to hammer the material 25 to be crushed. I have found that some materials, including coal, can be most effectively acted upon by a crusher of this kind. However, owing to the manner in which the projecting crushing elements repeatedly 30 hammer and break the material, the ring is subjected to several stresses, and the friction due to engagement with the material tends to rapidly wear away the projecting crushing elements, or hammers. To overcome the undesirable results of friction, I 35 preferably make the main body of the crushing ring of hard and inexpensive material, such as chilled cast iron, and to provide the desired strength, this frangible material is 40 preferably reinforced by a ring made of strong material, such as wrought iron, which does not engage the material to be crushed.

Figure I is a side elevation of a crusher 45 made in accordance with the present invention, a portion of the housing being broken away.

Fig. II is an enlarged side elevation of one of the new crushing rings.

Fig. III is a section of the ring shown in Fig. II.

The crushing device herein shown com-

prises a housing 1, a rotary shaft 2 mounted in said housing, and an arcuate grate 3 arranged in the housing. A rotary carrier 5 4, arranged in the housing and fixed to the rotary shaft 2, may be provided with any desired number of arms 5, each having a pin 6 and a crushing ring A loosely mounted on said pin. The pin 6 extends into the 60 opening 7 formed in the crushing ring.

The periphery of each crushing ring A is preferably corrugated to provide an annular row of projecting crushing elements, or hammers, 8 adapted to strike or hammer 65 the material to be crushed or broken.

The shaft 2 may be driven by any suitable power mechanism with the result of causing the crushing ring, or rings, A to travel around the axis of the shaft. Each 70 crushing ring A also rotates about its own axis, and the projecting crushing elements, or hammers, 8 repeatedly hammer and break the material to be crushed. Each projecting crushing element, or hammer, 8 is preferably in the form of a wedge-shaped rib, arranged transversely of the ring A to provide an elongated tapering hammer. Each of these projecting elements is rounded at its outer edge as shown in Fig. II. 80

Each crushing ring A is preferably made of hard frangible metal, such as chilled cast iron, and a reinforcing ring 9 made of relatively strong material, such as wrought iron, inclosed by said hard frangible metal. 85

I claim:

A ring of the character described having an annular row of projecting hammers adapted to successively strike the material to be broken, said projecting hammers and the body of said ring being made of chilled cast iron, and a reinforcing ring inclosed by said chilled cast iron, each of said projecting hammers being in the form of a wedge-shaped rib rounded at its outer edge and arranged transversely of the ring to provide an elongated tapering hammer, and the reinforcing ring being surrounded by and located adjacent to the annular row of projecting hammers. 95

In testimony that I claim the foregoing I hereunto affix my signature.. 100

THEODORE F. PHILIPPI.
